US00D768704S

(12) **United States Design Patent** (10) Patent No.: **US D768,704 S**
Choi et al. (45) Date of Patent: **** Oct. 11, 2016**

(54) **DISPLAY SCREEN OR PORTION THEREOF WITH GRAPHICAL USER INTERFACE**

(71) Applicant: **SAMSUNG ELECTRONICS CO., LTD.**, Suwon-si (KR)

(72) Inventors: **Arum Choi**, Incheon (KR); **Heuijin Kwon**, Seongnam-si (KR); **Youngsun Kim**, Suwon-si (KR)

(73) Assignee: **SAMSUNG ELECTRONICS CO., LTD.** (KR)

(**) Term: **15 Years**

(21) Appl. No.: **29/531,935**

(22) Filed: **Jun. 30, 2015**

(30) **Foreign Application Priority Data**

Dec. 31, 2014 (KR) 30-2014-0064365

(51) **LOC (10) Cl.** **14-04**

(52) **U.S. Cl.**

USPC **D14/488**; D14/486

(58) **Field of Classification Search**

USPC D14/485-488

CPC H04N 1/00196; H04N 1/0044; H04N 21/478; G06F 2203/04803-2203/04805

(57) **CLAIM**

We claim, the ornamental design for a display screen or portion thereof with graphical user interface, as shown and described.

DESCRIPTION

The FIGURE is a front view of a display screen or portion thereof with graphical user interface showing our new design.

The broken lines within the FIGURE show portions of the graphical user interface and the broken lines around the FIGURE showing of the display screen are included for the purpose of illustrating environment structure; the broken lines form no part of the claimed design.

1 Claim, 1 Drawing Sheet
